Primary Examiner — Karen E Kearney*Assistant Examiner* — Cary M Robinson(74) *Attorney, Agent, or Firm* — NSIP Law(57) **CLAIM**

We claim the ornamental design for a display screen or portion thereof with animated graphical user interface, as shown and described.

DESCRIPTION

FIG. 1 is the first image in a sequence for a display screen or portion thereof with animated graphical user interface showing our new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof; and,

FIG. 9 is the ninth image thereof.

The appearance of the animated user interface sequentially transitions between the images shown in FIGS. 1-9. The process or period in which one image transitions to another forms no part of the claimed design.

The two closely spaced broken lines at the perimeter in the figures illustrate a display screen or portion thereof and form no part of the claimed design. The remainder of the broken lines illustrate portions of the animated graphical user interface and form no part of the claimed design.
